MITTEN

Albert Lamb, Schenectady, N. Y., assignor to Gloversville Knitting Co., Gloversville, N. Y., a corporation of New York

Application April 22, 1949, Serial No. 2,191

Term of patent 14 years

(Cl. D3—11)

To all whom it may concern:

Be it known that I, Albert Lamb, a citizen of the United States, residing at Schenectady, in the county of Schenectady and State of New York, have invented a new, original, and ornamental Design for Mittens, of which the following is a specification, reference being had to the accompanying drawing, forming a part thereof, wherein:

Fig. 1 is a plan view of the back of a mitten, showing my new design;

Fig. 2 is a plan view of the front of the mitten shown in Fig. 1; and

Fig. 3 is an end elevational view of the mitten shown in Fig. 1.

The stippled horizontal areas indicate contrasting colors.

I claim:

The ornamental design for a mitten, as shown and described.

ALBERT LAMB.
